STANISLAS PICARD, OF PROVIDENCE, RHODE ISLAND, ASSIGNOR TO B. B. & R. KNIGHT CORPORATION, OF PROVIDENCE, RHODE ISLAND, A CORPORATION OF RHODE ISLAND

THREAD-EXTRACTING NEEDLE

Application filed March 20, 1929. Serial No. 343,512.

This invention relates to a thread extracting needle to be used in a thread removing machine as a preliminary step to hemstitching; and has for its object to provide a needle which will spread the threads which are adjacent those to be removed so as to prevent injury or rupture of the same during the time of deflecting of the threads to be removed from the fabric.

10 A further object of the invention is the spreading of the threads which it is desired should remain in the fabric by forming the needle with a dimension at right angles to the notched edges sufficient to spread the 15 threads as the needle is passed through the fabric.

With these and other objects in view, the invention consists of certain novel features of construction, as will be more fully described, and particularly pointed out in the appended claims.

In the accompanying drawings:

Fig. 1 is a front elevation of the needle.

Fig. 2 is a side elevation at right angles to 25 that shown in Fig. 1 of the needle.

Fig. 3 is a section of a fragmental portion of the needle showing the same as entering the fabric from which the threads are being removed.

20 Fig. 4 is a top plan view of the fabric with the needle in section showing its action upon the threads as it is initially passed into the fabric.

Fig. 5 is a view similar to Fig. 4 showing 25 the fabric after the needle has been passed through the same a plurality of times and the threads deflected with portions of the threads to be removed cut from the fabric.

Fig. 6 is a section of the fabric showing 30 the needle in position and taken substantially on line 6—6 of Fig. 5.

Fig. 7 is a section on line 7—7 of Fig. 5.

Fig. 8 is a section on line 8—8 of Fig. 3 showing the shape of the needle in cross section.

It is found in removing threads for hemstitching that as the threads to be deflected downwardly are received in notches in the needle that often the threads which should remain in the fabric are caught by these notches

and broken or ruptured and in order to avoid this undesirable result, I have provided a needle which has a dimension at right angles to the line joining the opposite notched edges of the needle such that it will spread the 55 threads which are to remain in the fabric and prevent their catching in the notches of the needle and being ruptured or broken thereby; and the following is a detailed description of the present embodiment of the invention 60 illustrating the preferred means by which these advantageous results may be accomplished.

With reference to the drawings, 10 designates the shank of the thread extracting 65 needle, which is substantially circular in cross section and adapted to be held in the jaws of the reciprocating head of a thread extracting machine. This needle is tapered at its end to provide a point 11 the shape of the cross section of the taper being square, as illustrated in Fig. 8, with the width of the needle substantially that of the width of the threads to be extracted from the cloth.

On two opposite corners 20 of the needle 70 I have provided a series of notches 12, 13 and 14 to engage the threads 15, 16 and 17 at either side of the center line 28 of the fabric, as illustrated in Fig. 5, to force these threads downwardly, as illustrated in Figs. 6 and 7, 80 into the path of the cutter or severing means for removing them from the cloth.

The edges 18 which are at right angles to the notched edges of the needle serve to engage the threads 19 of the fabric, as illustrated in Fig. 5, to spread the same, as illustrated in Fig. 4, and prevent them from being engaged by any of the notches in the edge 20 of the needle to be broken or abraded thereby.

In the initial stroke of the extracting 90 needle the threads to be removed are broken by the first plunge of the needle through the fabric after which the next subsequent reciprocation of the needle forces another portion of these threads downwardly; as the goods are fed forwardly and the subsequent strokes force the broken ends of the threads downwardly, as illustrated in Fig. 7, to be severed by the cutter and so on throughout 95 the length of the fabric to remove the threads 100

15, 16 and 17 on each side of the center line along which the point 11 of the needle acts.

I have found it of advantage to provide a plurality of notches on the needle so that should one notch fail to pick up the thread 5 to be removed a subsequent notch along the taper of the needle will be engaged by this thread to deflect it into the path of the cutter which acts upon the cloth in the usual manner 10 of the thread removing machine.

10 The foregoing description is directed solely towards the construction illustrated, but I desire it to be understood that I reserve the privilege of resorting to all the mechanical 15 changes to which the device is susceptible, the invention being defined and limited only by the terms of the appended claims.

I claim:

1. A thread extracting needle having a tapered fabric engaging end portion, two diametrically opposite thread engaging edges having spaced notches therein, and diametrically opposite smooth thread engaging edges positioned between the said notched edges.

25 2. A thread extracting needle having a tapered fabric engaging end portion of square cross-section, two diametrically opposite edges having spaced notches therein, the other two edges being smooth.

30 In testimony whereof I affix my signature.
STANISLAS PICARD.
